UNITED STATES PATENT OFFICE.

CHARLIE B. SMITH, OF KOKOMO, INDIANA.

STOVE.

Specification of Letters Patent. Patented Aug. 26, 1919.

1,314,440.

Application filed March 29, 1919. Serial No. 286,017.

To all whom it may concern:

Be it known that I, CHARLIE B. SMITH, a citizen of the United States, residing at Kokomo, in the county of Howard and State 5 of Indiana, have invented certain new and useful Improvements in Stoves; and I do hereby declare the following to be a full, clear, and exact description of the invention, such as will enable others skilled in the art 10 to which it appertains to make and use the same.

The present invention relates to stoves, and aims to provide a simple and inexpensive attachment for a heating stove to 15 facilitate the heating of the air in the room.

A further object is the provision of an air heating chamber to be disposed within the combustion chamber of the stove and provided with means for the inlet and outlet 20 of air and to support the chamber in place.

With the foregoing and other objects in view which will be apparent as the description proceeds, the invention resides in the construction and arrangement of parts hereinafter described and claimed, it being understood that changes can be made within 25 the scope of what is claimed without departing from the spirit of the invention.

The invention is illustrated in the accompanying drawing, wherein:—

Figure 1 is a vertical median section of a stove showing the air heating attachment in place.

Fig. 2 is a horizontal section taken on the line 2—2 of Fig. 1.

The attachment can be used on various heating stoves, and the stove illustrated includes the casing or drum 1 forming the combustion chamber, and a stove pipe 2 40 leads upwardly from the top of the casing to the back wall thereof of the outlet of the products of combustion.

In carrying out the invention, there is provided an air heating chamber 3 of vertically elongated form, and preferably pyramidal in shape, with its walls tapering upwardly. This chamber 3 is disposed within the combustion chamber adjacent to the rear wall of the casing, and said 45 chamber is provided adjacent to its lower larger end, with a boss 4 having an opening to threadedly receive a nipple 5 that is inserted through an opening in the back wall of the stove, and a nut 6 is threaded on the

nipple to clamp the lower portion of the 55 chamber against the back wall. The nipple 5 thus provides an inlet for fresh air, and assists in supporting the chamber in place. The upper smaller end of the chamber has an opening 7 into which is threaded the 60 lower end of a vertical outlet pipe 8 that extends upwardly through the outlet of the stove into the stove pipe 2, and an elbow 9 is secured on the upper end of the pipe 8 for the engagement of the nipple 10 inserted through an opening in the rear wall 65 of the pipe 2. A nut 11 is threaded on the nipple 10 to bear against the pipe 2 and assist in supporting the chamber 3 within the stove.

The device can be readily installed in almost any air heater, and the chamber 3 will be heated by the coals, thereby heating the air within the chamber which will rise and flow out through the pipe 8 and nipple 10, fresh air being admitted through the nipple 5 into the lower larger portion of the chamber which is adjacent to the bed of the fuel so as to efficiently heat the air. The products of combustion will also flow 80 upwardly around and along the walls of the chamber 3 and pipe 8, and will assist in heating the air, so that the present device will enhance the circulation of air and the heating of the room, especially with a small 85 fire or bed of coals. The tapering form of the chamber 3 will serve to increase or force the discharge of heated air through the pipe 8, thereby obtaining a greater circulation 90 through the chamber.

Having thus described the invention, what is claimed as new is:—

1. The combination with a stove and outlet pipe, of a vertically elongated air heating chamber within the stove below said 95 pipe, an air inlet nipple extending through the wall of the stove and engaging said chamber near the lower end thereof, and an air outlet pipe extending upwardly through the upper end of said chamber into 100 the first named pipe and discharging through the wall thereof.

2. The combination with a stove and its outlet pipe, of a vertically elongated air heating chamber within the stove below said pipe, 105 said chamber having a large lower end and tapering upwardly to a small upper end, an air inlet nipple extending through the wall

of the stove and attached to said chamber near the lower end thereof, an air outlet pipe extending upwardly from the upper end of said chamber into the first named pipe, and an air outlet nipple extending from the upper end of said pipe through the wall of the first named pipe.

Copies of this patent may be obtained for five cents each, by addressing the "Commissioner of Patents, Washington, D. C."

In testimony whereof I have signed my name to this specification in the presence of two subscribing witnesses.

CHARLIE B. SMITH.
